UNITED STATES PATENT OFFICE.

FREELAND W. OSTROM, OF NEWARK, AND IRVING F. WEBB, OF ELIZABETH, NEW JERSEY, ASSIGNEES TO THE SINGER MANUFACTURING COMPANY, A CORPORATION OF NEW JERSEY.

THREAD-CUTTING MECHANISM FOR SEWING MACHINES.

Application filed February 16, 1918. Serial No. 217,471.

To all whom it may concern:

Be it known that we, FREELAND W. OSTROM and IRVING F. WEBB, citizens of the United States, residing, respectively, at 5 Newark, in the county of Essex and State of New Jersey, and Elizabeth, in the county of Union and State of New Jersey, have invented certain new and useful Improvements in Thread-Cutting Mechanisms for 10 Sewing Machines, of which the following is a specification, reference being had therein to the accompanying drawings.

This invention relates to an improvement in thread-cutting mechanisms for sewing 15 machines and more particularly to thread-cutting mechanisms adapted to sever the chain of thread connecting articles sewed in rapid succession such as filled sacks and the like.

20 The invention has for its primary object to provide an improved construction adapted to automatically sever the chain of thread extending from sewed articles at a substantially uniform distance from the 25 articles regardless of the size of the articles being stitched.

A further object of this invention is to provide a continuously operated thread-cutter adapted to sever the thread, extending 30 from a sewed article, at the work side of the cloth-plate.

The invention has for a still further object to provide a continuously operated thread-cutter with means to positively direct 35 the thread extending from a sewed article into the path of operation of said thread-cutter.

Other objects of this invention will be apparent from the following description 40 and claims.

In its preferred embodiment, the present improvement comprises a thread-cutting mechanism substantially as disclosed in the U. S. patent to Albert Rontke, No. 1,156,821, 45 October 12, 1915 but having continuously operated connections with the actuating mechanism of the sewing machine. The cloth-plate of the sewing machine is provided with an opening through which the 50 thread-cutter is projected in its operating movements. Bridging said opening and extending in the direction of feed are raised work-directing members adapted to divert the stitched article out of the path of move-

ment of the thread-cutter, but permitting 55 a spring-pressed chain-directing member pivotally supported by the presser-foot to direct the thread extending from said article into the path of movement of the cutter, which severs the thread at the work side 60 of the cloth-plate as in the Rontke construction referred to.

The present improvement is particularly adapted for use in connection with filled 65 sack-sewing machines, but it is apparent that its use is not limited to that class of machines inasmuch as the thread will be positively directed into the path of movement of the cutter regardless of the plane in which the sewing machine cloth-plate 70 may lie.

In the accompanying drawings, Fig. 1 is a front side elevation of a filled-sack sewing machine of earlier construction, partly 75 broken off and embodying the present improvement. Fig. 2 is an end elevation, partly in section, of a portion of the sewing machine, illustrating the effective position of the thread-cutter mechanism and in dotted lines the position of the chain-directing member during the passage of the sack thereunder. Fig. 3 is a rear side elevation, partly in section of a portion of the sewing machine and showing the actuating 80 means for the thread-cutter blades. Fig. 4 85 is a perspective view of a portion of the sewing machine cloth-plate and including the material-diverting bridge. Fig. 5 is a perspective view of the chain-directing member. Fig. 6 is a fragmentary view 90 illustrating a portion of the automatic seam-controlling mechanism for the sewing machine as viewed in the direction indicated by the arrow A in Fig. 1.

The filled-sack sewing machine illustrated 95 comprises a base 1 from which rise the vertical standards 2 and 3 supporting the table 4. Mounted upon the table 4 is a bracket 5, carrying the overhanging sewing machine head 6, having stitch-forming mechanism of 100 well known construction and including a needle 7. The cloth-plate 8 of the sewing machine is provided with a throat-plate 9 having a feed-slot 10 traversed by the feed-dog 11, secured upon a feed-bar 12, pivoted 105 to the feed-rocker 13, actuated to impart feeding movements to the feed-dog by means of a pitman 14 from an eccentric on the

driving shaft 15 of the machine. The forward end of the feed-bar is pivotally connected to a pitman 16, having a strap embracing an eccentric on the driving shaft to 5 impart rising and falling movements to the feed-dog.

Opposed to the feed-dog is the presser-foot 17, secured to the presser-bar 18. The heel of the presser-foot is formed with 10 spaced bearing-lugs for a pivot-screw 19 upon which are fulcrumed the spaced apertured ears, as 20, of a resiliently controlled chain-directing member 21 having an inverted V-shaped chain-guiding surface 22. 15 A coil-spring 23 surrounds the pivot-screw 19, one end of the spring bearing against the shank of the presser-foot and the other end bearing upon the chain-directing member to normally hold said member in its lowered position. To permit the chain-directing member 21 to assume its desired lowered position, the cloth-plate is partly cut away to form an opening 24, merging into a transverse opening 25, for the passage of the 20 thread-cutter blades, hereinafter described. Bridging the openings 24 and 25 in the cloth-plate is a material-diverting device comprising bent wires 26 and 27 and adapted to prevent injury by the cutter-blades to the 25 stitched material.

The thread-cutter, as in the aforementioned patent, comprises a scissors arrangement consisting of thread-cutting blades 28 and 29. The blade 28 is pivotally supported 30 by means of a screw 30 upon a bracket 31 secured by screws, as 32, to the bed-plate of the machine, and the blade 29 is pivotally carried by a sliding bolt 33 movable in an elongated slot 34 formed in the bracket 31. 35 The blades 28 and 29 are yieldingly held against each other by means of a coil-spring 35 surrounding the pivot-bolt 36 passing through both blades. The action of the spring to withdraw the pivot-bolt from the 40 blades is resisted by a nut 37 secured upon the bolt. Pivotally secured to the sliding bolt 33 by means of a screw 38 threaded thereinto is one end of a thread-cutter actuating link 39 of which the other end is pivotally connected by means of a screw 40 with the free end of a rock-arm 42 secured by set-screws, as 43, upon an extension of the usual looper-actuating rock-shaft 44 common to the class of sewing machine employed and fully disclosed for instance in the U. S. patent to W. H. Hugg, No. 1,005,840, October 17, 1911. The means for actuating this rock-shaft from the driving shaft is so well known in the art that detailed description thereof is deemed unnecessary. It is evident from the foregoing description that the actuation of the stitch-forming mechanism of the sewing machine repeatedly projects the cutter-blades 28 and 29 45 through the opening 25 in the cloth-plate

and at the same time operates the blades in true scissors fashion. The stitched article after passing from under the presser-foot is raised above the path of operation of the cutter-blades by the material-diverting wires 26 and 27, the chain-directing member being lifted by the material and riding thereover. As the last stitched edge of the material passes the chain-directing member, the latter is caused, under the action of the spring 23, to assume its lowest position and as shown particularly in Fig. 2 of the drawings, to guide the chain of thread leading from the stitched article into the path of the cutter-blades 28 and 29, the continuous operation of which insures the severing of the chain at a substantially uniform distance from the stitched article. 70

The sack-conveyor frame 45 is supported by brackets 46 and 47 vertically adjustable 85 upon the standards 2 and 3. The conveyor-frame supports the carrier-belt 48 which may be driven in any suitable manner. In filled-sack sewing machines it is highly desirable to automatically control the period 90 of operation of the sewing machine and of the chain-severing device. To this end, trip-bars 49, (one only of which is shown) are provided upon crank-arms 50 and 51, fulcrumed upon rollers 52 and 53. To the 95 roller 53 is secured one end of a crank-arm 54, of which the other end is secured to a flexible connection 55.

The sewing machine is provided with a loose pulley 56 and a driving pulley 57 and 100 is driven from a motor 58 by means of a belt 59. Secured to the bracket 5 supporting the sewing machine is a bracket 60, having an upwardly extending arm 61 upon which is fulcrumed a belt-shifting lever 62, 105 normally held in stopping position by the provision at one end of a weight 63 and a brake-member 64. To the other end of the lever 62 is secured a supporting and directing member 65 for the flexible connection 110 55 which passes thereover, thence partly around similar members 66 and 67 and is connected with a suspended resistance member in the form of a weight 68.

In operation, the sewing machine remains stationary when the carrier-belt 48 is 115 started through commonly employed means. A filled sack is now placed upon the carrier-belt in advance of the trip-bars 49, which are depressed by the sack as it is 120 carried to and past the stitch-forming mechanism. The downward movement of the trip-bars rocks the crank-arm 54, exerting a pull upon the flexible connection 55. This pull is however resisted by the 125 weight 68, consequently swinging the belt-shifting lever 62 into starting position, thereby operating the sewing machine and the thread-severing device. As the mouth of the filled sack passes the material divert- 130

ing wires 26 and 27, the thread-cutter becomes effective to sever the chain as heretofore described. After the stitched sack rides past the end of the trip-bars 49, the 5 latter assume their raised position under the reverse action of the belt-shifting weight 63 thereby stopping the operation of the sewing machine.

Having thus set forth the nature of the 10 invention, what we claim herein is—

1. In a filled sack sewing machine, the combination with a cloth-plate, stitch-forming mechanism including a reciprocating needle, and feeding mechanism including a feed-dog with actuating means for said mechanisms, of a thread-cutter operatively connected with said actuating means, and a cutter-guard projecting outwardly from said cloth-plate substantially in the 15 direction of reciprocation of the needle to direct the sack mouth outside the field of cutter-actuation rearward of the point of seam-formation.

2. In a filled sack sewing apparatus, in combination, stitch-forming mechanism, means for conveying a filled sack past said stitch-forming mechanism, automatic controlling means for determining the period of operation of said stitch-forming mechanism, 20 a thread-cutter having a path of operation intersecting the plane of the sack mouth at the point of seam-formation, means for continuously operating said thread-cutter during the period of operation of said 25 stitch-forming mechanism, and means for diverting the stitched sack mouth out of the path of operation of said thread-cutter.

3. In a filled sack sewing machine, in combination, stitch-forming and feeding 30 mechanisms, a cloth-plate, a thread-cutter having a path of operation substantially at right angles to the line of seam-formation and its effective cutting position on the work-side of the cloth-plate, means for continuously operating said thread-cutter, and 35 means for diverting the filled sack mouth out of the path of operation of said thread-cutter and permitting the latter to sever the sewing-thread extending from the stitched 40 sack.

4. A sewing machine including in combination, stitch-forming and feeding mechanisms, a cloth-plate, an opening in said cloth-plate in the rear of the stitch-forming 45 mechanism, a thread-cutter comprising a pair of movable cutting blades having an operative path of movement through said opening intersecting the plane of the article being stitched at the point of seam-formation, 50 means for continuously operating said thread-cutter, and means for directing a

stitched article out of the path of movement of said thread-cutter.

5. In a filled sack sewing machine, the combination with a cloth-plate, stitch-forming and feeding mechanism, and means for actuating said mechanism, of a thread-cutter having a path of operation substantially at right angles to the line of seam-formation, means for operating said thread-cutter, and a yieldingly mounted thread-chain positioning member having a thread-engaging portion located at the rear of the 65 rearward limit of feed-movement of the feeding mechanism for positioning a thread-chain below the plane of said cloth-plate to be engaged and severed by said thread-cutter.

6. In a filled sack sewing machine, the combination with a cloth-plate, stitch-forming and fabric feeding mechanism, and actuating means for the latter, of a thread-cutter having a cutting portion operative 70 above the plane of said cloth-plate and operatively connected with said actuating 75 means, and a thread-chain positioning member for positioning a thread-chain below the plane of said cloth-plate to be engaged and severed above the latter by said thread-cutter.

7. In a filled sack sewing machine, the combination with a stitch-forming mechanism, a fabric feeding mechanism, a presser-foot, and actuating means for said mechanisms, of a thread-cutter operatively 95 connected with said actuating means, a thread-chain positioning member provided with a thread-chain guiding surface and hinged to said presser-foot, and means for directing a filled sack outside the field of 100 cutter-actuation, said chain-guiding surface, directing means and thread-cutter being located at the rear of the rearward limit of feed-movement of the feeding mechanism.

8. In a sewing machine, the combination 105 with stitch-forming and feeding mechanism, of a thread-chain positioning member having movements in a direction substantially transverse to the plane of the fabric being stitched, a thread-cutter, and 110 means for actuating the thread-cutter to sever a chain of thread, said thread-cutter actuating means including devices for imparting to the thread-cutter movements in a direction opposed to said movements of the 115 thread-chain positioning member to tighten said chain during the severing of the same.

In testimony whereof, we have signed our names to this specification.

FREELAND W. OSTROM.
IRVING F. WEBB.
